(57) CLAIM

The ornamental design for an egg carton, as shown and described.

DESCRIPTION

FIG. 1 is a perspective top view of another embodiment of my egg carton in an open configuration;
 FIG. 2 is a close-up of the area designated as 2 in FIG. 1;
 FIG. 3 is a close-up of the area designated as 3 in FIG. 1;
 FIG. 4 is a perspective bottom view of the egg carton shown in FIG. 1;

FIG. 5 is a close-up of the area designated as 5 in FIG. 4;
 FIG. 6 is a top view of the egg carton shown in FIG. 1;
 FIG. 7 is a close-up of the area designated as 7 in FIG. 6;
 FIG. 8 is a close-up of the area designated as 8 in FIG. 6;
 FIG. 9 is a close-up of the area designated as 9 in FIG. 6;
 FIG. 10 is a bottom view of the egg carton shown in FIG. 1;
 FIG. 11 is a front elevation view of the egg carton shown in FIG. 1;

FIG. 12 is a back elevation view of the egg carton shown in FIG. 1;

FIG. 13 is a first side elevation view of the egg carton shown in FIG. 1;

FIG. 14 is a close-up of the area designated as 14 in FIG. 13;
 FIG. 15 is a second side elevation view of the egg carton shown in FIG. 1;

FIG. 16 is a perspective top view of the egg carton shown in FIG. 1 in a closed configuration;

FIG. 17 is a close-up of the area designated as 7 in FIG. 16;
 FIG. 18 is a perspective bottom view of the egg carton shown in FIG. 16;
FIG. 19 is a close-up of the area designated as 19 in FIG. 18;
 FIG. 20 is a top view of the egg carton shown in FIG. 16;
FIG. 21 is a bottom view of the egg carton shown in FIG. 16;
 FIG. 22 is a front elevation view of the egg carton shown in FIG. 16;
FIG. 23 is a close-up of the area designated as 23 in FIG. 22;
 FIG. 24 is a back elevation view of the egg carton shown in FIG. 16;

FIG. 25 is a first side elevation view of the egg carton shown in FIG. 16; and,

FIG. 26 is a close-up of the area designated as 26 in FIG. 25.
 The broken lines shown in the drawings illustrate portions of my egg carton that form no part of the claimed design. The oblique line shading shown in the drawings indicates a transparent or translucent surface. The portions that would be visible behind the transparent or translucent surface are omitted for a clear disclosure of the surface configuration.
